SLOT CAR RACING TABLE

William H. Smedley, 6012 Dudman St., Garden Grove,
Calif., and Glenn H. Adkins, 8637 Vicki Drive, Whittier, Calif.

Filed Sept. 23, 1965, Ser. No. 87,144

Term of patent 14 years

(Cl. D34—5)

Fig.-2

The dominant features of the design reside in the portions shown in solid lines.

We claim:

The ornamental design for a slot car racing table, substantially as shown and described.
